UNITED STATES PATENT OFFICE.

JONATHAN FORSHAY AND CHRISTIAN G. HIRLINGER, OF PHILIPSBURG, PENNSYLVANIA.

WRENCH.

SPECIFICATION forming part of Letters Patent No. 314,572, dated March 31, 1885.

Application filed September 10, 1884. (No model.)

To all whom it may concern:

Be it known that we, JONATHAN FORSHAY and CHRISTIAN G. HIRLINGER, citizens of the United States, residing at Philipsburg, in the county of Centre and State of Pennsylvania, have invented a new and useful Improvement in Wrenches, of which the following is a specification, reference being had to the accompanying drawings.

10. This invention relates to wrenches, and to that class of the same which employ a sliding jaw; and it has for its object to provide a device of this character which shall possess superior advantages in point of simplicity and durability in construction, and convenience and efficiency in operation.

A further object of the invention is to provide a wrench for turning nuts which shall be capable of various adjustments, and which 20 shall have a firm hold on the article to be turned, so that there will be no possibility of its slipping when in operation.

With these ends in view the said invention consists in certain details of construction and 25 combination of parts, as hereinafter set forth, and particularly pointed out in the claims.

In the accompanying drawings, Figure 1 is a perspective view of our improved wrench, showing the latter in its open position. Fig. 30 2 is a rear view of the same in the closed position. Fig. 3 is a longitudinal section on the line $x-x$, Fig. 2. Fig. 4 is a transverse section on the line $y-y$, Fig. 3. Fig. 5 is a transverse section on the line $z-z$, Fig. 3.

35. Like letters are used to indicate corresponding parts in the several figures.

Referring to the drawings, A designates the shank of our improved wrench, having a stationary jaw, B, formed therewith at one end, 40 and a handle, C, at the opposite end.

D designates a sliding stem working in guide-loop E, projecting from the stationary shank A, and carrying a sliding jaw, F, at one end, said stem being arranged parallel to and 45 sliding upon the shank. A band or collar, G, clasps the other end of the stem and encircles the shank, an opening, a , being formed in the latter to allow the passage of a pin or bolt, H, headed at each end, as at b d , the head b working through an opening in the band or collar G, and the other end passing through an opening,

e , of the band or collar, and an elongated slot, f , of an adjusting-piece, I. A coiled spring, J, is arranged in the opening a of the shank, and bears at one end against the head b of the pin H, and at the other end against the inner face of the shank. It will be seen that the tension of this spring serves to hold the head d against the adjusting-piece I, to retain the latter in the position to which it may be adjusted. The adjusting-piece I lies flat against the face of the band or collar G, and has one of its ends turned or curved outward to form a bearing-edge, g , for the thumb, its other end being turned inward at right angles, as at h , 60 a stud or pin, K, extending inward from said end h , and passing through an opening, i , in the band or collar G, entering any one of a series of openings, j , in an adjustable plate, L, and received into a recess of the stem D. This 65 adjustable plate is interposed between the band or collar G and the outer face of the stem, and is of a length sufficient to accommodate various adjustments of the tool, the lower end of the plate having an enlargement, k , perforated as shown. A bifurcated connecting piece or bar, M, clasps the enlargement, and is connected thereto by a pin or rivet, l , the other end of the connecting-bar being pivoted within the slotted upper end of the operating 70 handle or lever N. The latter is curved at the upper end, and is pivoted to the lug or projection O, which extends from the shank A, and when not in operation it rests flat against the handle end of the shank. 75

The operation of our invention will be readily understood from the foregoing description, taken in connection with the annexed drawings.

In applying our improved wrench for turning nuts, the handle or lever N is drawn out, as seen in Fig. 1, so as to cause the stem D to slide upward, when by the inward movement of the handle or lever the stem D is caused to work downward, and its jaw clasp, in connection with the jaw of the shank, the article to be turned. Should the space between the two jaws be insufficient to clasp the article, the sliding stem may be adjusted farther up by sliding the adjusting-piece I until its pin or stud 85 K is withdrawn from the hole in the adjustable plate L. The latter is then set farther 90 100

down, when the piece I is operated or slid back into its normal position, the pin K passing through a hole in the plate L nearer its upper end than in the previous adjustment. In this 5 manner the jaw at the end of the sliding stem will be set farther away from the jaw of the shank, so as to afford a greater adjustment than formerly, the operation of the handle or lever N causing the two jaws to act in conjunction to engage the article to be turned. 10 The spring inclosing the pin or bolt H serves to hold the head d against the adjusting-piece I, so that in adjusting the latter it is not necessary to loosen and then tighten a screw, as 15 in the former method of adjustment, since the piece I may be slid in and out by simply removing the pressure of the head d of the bolt H against said piece, the spring returning the bolt to its original position. The jaws B F 20 have a hole, m, pierced through each to receive pins or bolts n, the latter serving as a means of attaching wearing-plates p p, which are U-shaped in cross-section, as seen in Fig. 5. The said plates p have teeth o, which engage 25 with the article to be turned. By this arrangement we may detach the plates p, the teeth of which are coarse, and substitute therefor plates of the same form having finer teeth when turning small articles. We may also 30 attach plates concave in cross-section and of such a form as to be applicable in turning pipes and the like, and for this reason we do not wish to be limited to the character of the plates or the form thereof which may be attached to the jaws of the wrench. 35 Our improved wrench is simple in construction, convenient in operation, and efficient in use. By means of the same we are enabled to accommodate the wrench to various sizes 40 of nuts or other articles to be turned. The wrench affords a firm hold on the articles, and there will be no chance of slipping the hold when in operation. The action is positive and certain, and the arrangement is such that

there is no possibility of its working out of 45 order.

Having described our invention, we claim—

1. In a wrench, the combination, with the shank carrying a jaw at one end, of a sliding stem carrying a jaw, a pivoted handle or lever, and means, substantially as described, for connecting the latter with the stem, said means being adjustable in length, as and for the purpose set forth. 50

2. In a wrench, the combination, with the shank carrying a jaw at one end, of the stem sliding on said shank and carrying a jaw, a band or collar rigidly held to the stem and sliding on the shank, the pivoted handle or lever, the adjustable plate connecting with the handle or lever, and means for attaching the plate to the stem at any point of the length of said plate, as set forth. 55

3. In a wrench, the combination, with the shank carrying a jaw, of the stem sliding on said shank and carrying a jaw, the pivoted handle or lever, a perforated plate held at any point of its length on the stem, and a connecting-bar for attaching the plate to the handle or lever, as set forth. 65

4. In a wrench, the combination, with the shank carrying a jaw, of the stem sliding on the shank, and also carrying a jaw, a band or collar connecting the shank and stem, a spring-pressed pin or bolt securing the band to the stem, an adjusting-piece held in place by the head of the said bolt, a pin on one end of the said piece, a perforated plate arranged to be engaged by the said pin, and a handle or lever connecting with the plate, as set forth. 75

In testimony that we claim the foregoing as our own we have hereto affixed our signatures in presence of two witnesses.

JONATHAN FORSHEY.

CHRISTIAN G. HIRLINGER.
